UNITED STATES PATENT OFFICE.

OTTO C. HOFFMANN, OF CHICAGO, ILLINOIS, ASSIGNOR TO WILLIAM W. MERRILL, OF CHICAGO, ILLINOIS.

FUSE.

No. 835,618.

Specification of Letters Patent.

Patented Nov. 13, 1906.

Application filed February 26, 1904. Serial No. 196,348.

To all whom it may concern:

Be it known that I, OTTO C. HOFFMANN, a citizen of the United States, residing at Chicago, in the county of Cook and State of Illinois, have invented a certain new and useful Improvement in Fuses, of which the following is a specification.

My invention relates to fuses.

I wish to produce an inclosed fuse capable of various uses, economical in its manufacture, and efficient.

I have illustrated my invention by the accompanying drawings, wherein—

Figure 1 is a side elevation with parts broken away; Fig. 2, a plan view; Figs. 3 and 4, views of the terminal blank; Fig. 5, a cross-section through the terminal tube; Fig. 6, a side elevation with parts broken away of an incomplete fuse, and Fig. 7 is an elevation of a complete fuse.

A is a block on which are mounted two terminal plates B B, associated with screws C C, whereby the circuit-wires may be connected to these terminals.

Arising from the terminals B B are the spring portions D D, adapted to clamp between them the flattened ends of the fuse.

E is a tube of glass or other suitable material.

F is a blank of copper shaped as shown. Such blanks may be cut out of continuous strips or plates without loss of material. At one end of the blank is a projection G, which is preferably first turned up into the position indicated in Fig. 4 substantially at a right angle to the body of the blank. This may be done by putting the piece G into a slot in an arbor and then bending the blank around the arbor, so as to form the tube H with the in-

wardly-projecting piece G, which now becomes a stop for the end of the tube E, as indicated in Fig. 6. The parts will be brought together after the terminal tubes are so made in the manner indicated at Fig. 6, and they

will be cemented at J. The fuse-wire K may now be passed through the three tubes so arranged, whereupon the metal tubes may be flattened at their ends beyond the glass tube to form the finished fuse illustrated in Figs.

1, 2, and 7. These flattened ends are suitable to be inserted between the spring-pieces D D, whereupon the circuit is made through the inclosed fuse-wires. If the fuse is to be attached in some other manner, slots L or M

may be stamped in the flattened ends, so as 55 to permit such attachment.

It will be readily understood that I do not wish to limit myself to any particular size, shape, or proportion of the several parts or to the use of any particular materials, though 60 what I have illustrated in Figs 1 and 2 is two line-terminals of spring-brass, two fuse-terminals of thin copper sheet, a glass-inclosing tube, and the usual fuse-wire.

The use and operation of my invention is 65 apparent. I may, however, briefly refer to some of its peculiarities, advantages, and to the means by which it is produced.

By firmly flattening the ends of the fuse-terminals the fuse-wire is grasped between 70 them without the need of solder or the like. Moreover, the fuse-wire is firmly and securely protected. These flattened ends should now be tightly clamped, as by the spring-pieces of Figs. 1 and 2, or by the clamping-screws 75 passed through the slots. (Illustrated in Fig. 7.) This holds the flattened sides of the terminal together and makes a permanent contact between the fuse-wire and the fuse-terminals without the use of solder or other 80 means of securing the parts together. The ends should be flattened at a distance from the ends of the glass tube, so as to avoid breaking the latter. The fuse-terminal extends beyond the glass, and therefore in clamping or 85 attaching the same it is unnecessary to put any pressure upon the inclosing tube. The flat terminals obviously present a greater width than the diameter of the tube, and therefore they furnish a convenient means 90 of attaching the fuse without bringing the glass of the tube into contact with any of the supporting parts.

The fuse-wire is entirely inclosed, but has a free air space or chamber. In the process of 95 manufacture, as above outlined, the tubular fuse-terminals are provided with an inward stop, which can be made in any desired way, and I have shown but one, against which the ends of the tubes rest. Thus I obtain terminals of uniform length. Of course the fuse-wire could be attached in other ways and the parts could be soldered, or the fuse-wire could be brought through the terminal and there soldered. What I have shown 100 seems to be the most convenient and least expensive method of carrying out my invention. Among other things this construction per-

mits me to use a tube with a fuse-wire passing substantially along the axis of the tube, because I have terminals which project beyond the ends of the tube lie partially in the plane of the axis thereof, and to them the fuse-wire is attached beyond the ends of the tube.

I claim—

1. A fuse comprising a tube with flattened tubular terminals inclosing the ends of the tube, such flattened portions of the terminals being wider than the diameter of the tube, a fuse passing through the tube and connected to the terminals and a stop within the tubular part of each of the terminals between the end of the tube and the flattened end of the terminal.
2. A fuse comprising a tube, two terminals, one at each end, each terminal having a flattened portion beyond the end of the tube and a stop to abut the tube, such stop being a projection from the wall of the terminal extending inwardly therefrom and a fuse within the tube and connected to the terminals.
3. A fuse comprising a tube, two terminals each having three parts, one a tubular part to inclose the end of the tube, another a flattened portion projecting beyond the tube, and the third a stop within the tubular part to abut the end of the tube within the terminal, and a fuse within the tube and attached to the terminals.
4. A fuse comprising a tube, a fusible conductor, devices to support such tube and make terminals for such conductor, each of such devices composed of a blank of conducting material with a projection on one edge, such blank being bent so as to form a tubular device with the projection extending therein, such device being flattened at one end beyond such projection.
5. A fuse comprising a tube, two terminals, one at each end, each having three parts, one

part to the end of the tube, another a flattened portion projecting beyond the tube, 45 and the third a stop comprising a portion of the terminal projecting beyond the tubular part to abut the end of the tube and a fuse within the tube, and attached to the terminals.

6. A fuse comprising a tube with flattened tubular terminals biting the ends of the tube, such flattened portions of the terminals being wider than the diameter of the tube, a fuse passing through the tube and connecting 55 with the terminals, and a stop forming a part of the terminal for preventing the terminal from engaging the tube too far from its extremity located between the tubular portion and the flat part of the flattened end. 6c

7. A fuse comprising a tube with flattened tubular terminals biting the end of the tube, such flattened portions of the terminals being wider than the diameter of the tubular portion of the terminal, a fuse passing through 65 the tube and connecting with the terminals and a stop forming a part of the terminal for preventing the terminal from engaging the tube too far from its extremity located between the tubular portion and the flat part 70 of the flattened end.

8. A fuse comprising a tube with flattened tubular terminals biting the ends of the tube, such flattened portions of the terminals being wider than the diameter of the tube, a fuse 75 passing through the tube and connecting with the terminals, and a stop forming a part of the terminal for preventing the terminal from engaging the tube too far from its extremity and cement between the terminal 80 and the tube.

OTTO C. HOFFMANN.
